SURGICAL SUPPORT

Max L. Holycross, Columbia City, Ind.

Application November 18, 1946, Serial No. 710,598

4 Claims. (Cl. 128—100)

1

This invention relates to improvements in a surgical support adaptable for use by a person afflicted with a floating kidney to prevent wandering thereof.

It has been found that the ordinary abdominal truss used for sustaining internal organs in normal position is inadequate for confining a floating kidney in its normal place because of the tendency of the pressure pad to move or become shifted from its intended location on the abdomen.

In the instant invention the pressure pad is held definitely where initially applied regardless of contortions of the body of the patient occasioned in walking or maneuvering about.

An object of the invention is to afford a surgical appliance in which is included a pressure pad, a girdle, and a frame so arranged that when the appliance is worn by a patient afflicted with a floating kidney, the pad is sustained in the initial position intended and is undisturbed by normal movements of the patient.

Another object of the invention is to afford a construction in which the parts thereof are readily separable or re-assembled and conveniently adjusted when the appliance is fitted on the patient.

Other objects and advantages of the invention appear in the following description.

An illustrative embodiment of the invention is shown in the accompanying drawing, in which:

Fig. 1 is a perspective view of an appliance in which the invention is incorporated, viewed from the front;

Fig. 2 is a perspective view of a spring frame forming a part of the appliance;

Fig. 3 is a top plan view of the pressure pad;

Fig. 4 is a side elevational view of the pad shown in Fig. 3, partially in section; and

Fig. 5 is a detail elevational view showing the pressure pad and its situs, the view being in section.

The illustrative embodiment of the invention consists of a girdle 6, a spring frame 7, an adjustable fastening, indicated generally by A, and an unattached pressure pad 8.

The girdle 6 is preferably formed of two oppositely disposed fabric pieces 9—10 the front ends of which overlap and are secured together by snap fasteners 11, and the rear ends of which are spaced apart and adjustably secured together by a lacing 12, as in the usual manner, by which to take up slack of the girdle when in place. Upon the front face of the fabric piece 9 is secured a pocket 13 preferably of fabric, the far end 14 of which is open. The girdle is equipped with customary crotch straps 15.

The frame 7 is preferably constructed of spring wire, bent to form a U-shaped loop 16 at one end of the frame, and parallel arms 17, contiguous with the loop, the distal ends of which are

2

back-turned to form eyes 18. The arms are spaced apart from each other and bent to partially encompass the girdle so that the loop and the distal ends of the arms overlap the front faces of the girdle pieces. The loop end of the frame extends into the pocket 13, when the frame is in place on the girdle, and the distal ends of the arms are secured to a draw string 19 which is attached to the girdle at 19' and strung through the eyes 18 and connected with a pull cord 20 that is secured to an anchor button 21 on the front of the fabric piece 10.

The pressure pad 8 is made of elastic material, such as rubber or sponge rubber and shaped 15 to suit that form of depression required to be made in the abdominal wall. The elastic body 8 is completely encased within a covering 8' of fabric by which the elastic material is prevented from having direct contact with the flesh of the 20 patient.

In use, the girdle is placed around the waist and secured by closing the snap fasteners 11 and tightening the lacing 12 so the girdle fits snugly in place around the torso. The frame 7 is positioned around the girdle with its arms 17 disposed astride the hip bones and with its loop end extending into the pocket 13 and may be further secured, if desired, by stitches 22 to more firmly hold the arms and the girdle together. The distal ends of the arms are drawn into a selected position by manipulating the fastening A, and are held in place by securing the pull cord 20 around the anchor button 21. After the girdle and the 25 frame have been assembled and adjusted to suit the comfort of the patient, the pressure pad is then bodily inserted between the inner wall of the girdle, back of the pocket 13, and the adjacent wall of the abdomen whereupon the pad becomes 30 impressed into the loop end 16 of the frame and forms an impression in the adjacent wall of the abdomen, thus to locally restrict movement of adjacent internal organs.

45 A valuable feature of the invention is that the pressure pad is unattached with respect to the girdle or the frame and is held in place definitely in the impression made by the pad in the abdominal wall by pressure of the girdle.

50 Relative movement of the pad and the girdle is limited by the bulging of the outer wall of the pad within the loop end of the frame. This arrangement is advantageous in that the pad is held in the impression made by it in the abdomen while the outer face of the pad has limited 55 freedom of movement relative to the confining girdle. In this manner friction between the pad and the flesh of the patient is averted.

Variations from the particular construction above disclosed may be resorted to by the exer-

use of skill in the art, without departure from the spirit or scope of the invention.

What I claim is:

1. A surgical support for floating kidney consisting of a girdle, a frame partially encompassing the girdle shaped to provide a loop end and contiguous parallel arms spaced apart from each other, said loop end and the distal ends of said arms overlapping the front of the girdle, means securing said loop end in a definite position on the girdle, an adjustable fastening connecting the distal ends of the arms to the girdle, and an unattached pressure pad disposed back of the loop end of the frame between the girdle and adjacent wall of the abdomen.

2. A surgical support for floating kidney consisting of a pliant girdle provided with a pocket overlying a front portion thereof, a frame having a loop end, secured in said pocket, and contiguous parallel arms spaced apart from each other partially encompassing the girdle, an adjustable fastening on the front of the girdle opposite said pocket connected with the distal ends of said arms, and an unattached elastic pressure pad disposed between the abdomen of the wearer and the girdle back of the loop end of the frame, said loop end constituting a situs for said pad.

3. A surgical appliance for a floating kidney consisting of a pliant girdle provided with a frame having a loop end secured on a front side portion

of said girdle and contiguous parallel arms spaced apart from each other and partially encompass the girdle, the distal ends of which arms overlap the opposite front side portion of said girdle, an adjustable fastening means on the girdle connected with said arms to secure the frame in place, and an unattached pressure pad, disposed between the girdle and the abdomen of the wearer, seated in said loop end.

10 4. A surgical appliance for floating kidney consisting of a girdle, a frame secured to and partially encircling said girdle, said frame being shaped to provide a loop and contiguous parallel arms, means for securing said frame in a selected position on said girdle, and an unattached pressure pad disposed between the girdle and the abdomen of the wearer back of the loop so as to be seated therein thus to retain the pad in operative position.
